INVENTOR

UNITED STATES PATENT OFFICE

OWEN H. SPENCER, OF INDIANAPOLIS, INDIANA

COOLING MEANS FOR ENGINE STRUCTURES AND CYLINDER HEADS THEREFOR

Application filed June 27, 1930. Serial No. 464,390.

This invention relates to cooling means for engine structures and cylinder heads therefor and particularly to internal combustion engines and one feature of the invention is the provision of means for directing a cooling medium to both the interior and exterior of the engine structure and cylinder head, from a single source of supply.

A further feature of the invention is the provision of means for directing air through a passage formed beneath the intake and exhaust channels of the engine head.

A further feature of the invention is the provision of means for forming a forced draft through the passages beneath the intake and exhaust channels.

A further feature of the invention is the provision of means for reinforcing the walls of the intake and exhaust channels.

Other objects and advantages will be hereinafter more fully set forth and pointed out in the accompanying specification.

In the accompanying drawings which are made a part of this application,

Figure 1 is a top plan view of an engine cylinder head.

Figure 2 is a sectional view thereof as seen along line 2-2, Fig. 1, showing the head attached to an engine.

Figure 3 is a detail sectional view as seen along line 3-3, Fig. 1, and,

Figure 4 is a sectional view as seen along line 4-4, Fig. 3.

Referring to the drawings in which similar reference numerals designate corresponding parts throughout the several views, the numeral 1 designates the cylinders of an engine, of the internal combustion type, said cylinders having air inlet ports 2 and exhaust ports 3 in the lower portion therefor, which are controlled by means of pistons 4. The air is fed to the ports 2 from an air supplying manifold 5, the air on leaving the manifold passing through an air chamber 6 before communicating with the ports 2, while the exhaust passes from the ports 3 into an exhaust manifold 7.

At the upper end of each cylinder of the engine is a head 8, in which is mounted a fuel control valve 9 and an exhaust valve 10, fuel

being conveyed to the port 11, controlled by the valve 9, through a channel 12, while the exhaust from the port 13, controlled by the valve 10, is conveyed to the manifold 7, through a channel 14.

As the ports 11 and 13 are substantially at the axial center of the head 8 and as the channels 12 and 14 extend from the ports 11 and 13 to points beyond the edge of the head 8, an air passage 15 is formed between the head proper and the walls of the channels 12 and 14, through which a current of air passes for cooling the head at this point and thus maintain that portion of the head below the channels at substantially the same temperature as the remainder of the head.

The heads 8 are secured to their respective cylinders by means of hollow bolts 16, the lower ends of which extend downwardly through openings 17 in the head and are threaded into sockets 18 on the cylinders 1, the outer ends of the bolts being also threaded to receive nuts 19. As a bolt 16 passes between the channels 12 and 14 and one at the outer edges of said channels, reinforcing ribs 20 are extended between the under faces of the channels 12 and 14 to the adjacent portion of the head 8, said ribs being on opposite sides of the path of the bolt 16 passing between the channels so as not to interfere with the free passage of air through the air passage 15. These ribs receive the strain incident to the tightening of the nuts 19 on the bolts 16 and prevent bending or yielding of the walls of the channels 12 and 14.

The inner ends of the bolts 16 communicate with a jacket 21, formed around the cylinder 1, adjacent the upper end thereof, so that a current air will be passing outwardly through the hollow bolts when the engine is running thus materially aiding in cooling the cylinder head and parts associated therewith and by forming a port 22 in the bolt 16 passing between the channels 12 and 14, an air current is induced through the air passage 15.

A current of air is conducted from the manifold 5 to the jacket 21 through the medium of a pipe 23, and so long as the air charging mechanism 24 is in action, for supplying air to the ports 2 a constant flow of air

will be directed through the jacket 21 and bolts 16.

In addition to cooling the engine at the points receiving the maximum heat by passing air through the jacket 21, the air escaping from the outer ends of the bolts 16 will flow over the exterior of the engine and aid in cooling the same.

What I claim is:

- 10 1. In a cooling means for engines, the combination with a cylinder and head construction of an engine, of an external air enclosure means formed by said structure, and means for directing a cooling medium to the interior and exterior of said construction, and to said enclosure means from a single source of supply.
- 20 2. In a cooling means for engines, a cylinder head having an intake and exhaust port therein, curved and substantially parallel channels communicating with said ports, and an air passage formed between said channels and the contiguous parts of the cylinder head.
- 25 3. In a cooling means for engines, a cylinder head having an intake and exhaust port therein, substantially parallel channels communicating with said ports, an air passage formed between said channels and the contiguous parts of the cylinder head.
- 30 4. In a cooling means for engines, a cylinder head having an intake and an exhaust port therein, substantially parallel channels communicating with said ports, an air passage formed between said channels and the contiguous portions of the head, members spanned between said channels and said head, apart from the junctures of said channels and heads, whereby said channels are reenforced without obstructing the movement of air at said juncture.
- 35 5. In a cooling means for engines, a cylinder head having an intake and exhaust port therein, channels communicating with said ports, an air passage formed between said channels and the contiguous portions of the head, members spanned between said channels and said head, apart from the junctures of said channels and heads, whereby said channels are reenforced without obstructing the movement of air at said juncture.
- 40 6. In a cooling means for engines, a cylinder head construction having an intake and an exhaust port therein, external air tributary means associated with said structure for cooling same, channels communicating with said ports, an air passage between said channels and the contiguous parts of the cylinder head, and means for inducing draft through said passage and tributary means from a common source.
- 45 7. In a cooling means for engines, a cylinder having an air inlet adjacent its lower end, an external air enclosure associated with the wall of said cylinder, means for supplying air to the exterior of said cylinder, and to said

enclosure and said air inlet from a common source.

8. The combination with the cylinder and head construction of an internal combustion engine, with an external duct and external tributaries leading therefrom associated with the wall of such construction, and a means for directing air to the interior of the combustion portion of such construction and to said duct from a common source, for cooling such construction.

In testimony whereof, I have hereunto set my hand on this the 26th day of June, 1930.

OWEN H. SPENCER.
